Term of patent 14 years

Int. Cl. D25—04

U.S. Cl. D13—1

FIG. 1 is a top plan view of an airport terminal showing my new design;

FIG. 2 is a perspective view of hangars used therein; and

FIG. 3 is a prospective view thereof.

This application is a continuation-in-part of my pending application, Serial No. D.4,340, filed Oct. 19, 1966, and now abandoned.

The characteristic features of my design reside in the portions shown in full lines as shown, it being understood, however, that the broken line disclosure constitutes part of the claim.

I claim:

The ornamental design for an airport terminal, as shown and described.
